(57) **CLAIM**

The ornamental design for a pod holder, as shown and described.

DESCRIPTION

FIG. 1 is a perspective view as seen from the top, front and right side of a pod holder for a beverage maker showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view as seen from the bottom and left side of the pod holder.

The broken lines in the drawings are included for illustrative purposes only and form no part of the claimed design.
